UNITED STATES PATENT OFFICE.

GILBERT E. ALPHIN, OF MOUNT OLIVE, NORTH CAROLINA.

COMBINED SHADE-ROLLER AND CURTAIN-POLE SUPPORT.

1,075,182.

Specification of Letters Patent.

Patented Oct. 7, 1913.

Application filed May 19, 1913. Serial No. 758,642.

To all whom it may concern:

Be it known that I, GILBERT E. ALPHIN, a citizen of the United States, residing at Mount Olive, in the county of Wayne and 5 State of North Carolina, have invented certain new and useful Improvements in Combined Shade-Roller and Curtain-Pole Supports; and I do declare the following to be a full, clear, and exact description of the invention, such as will enable others skilled in the art to which it appertains to make and 10 use the same.

This invention relates to improvements in combined adjustable shade rollers and curtain pole supports.

One object of the invention is to provide a combined shade roller and curtain pole bracket or support having means whereby the same may be applied to and secured in 20 position on window frames of various widths without the use of separate fastening devices.

Another object is to provide a support of this character having shade roller receiving brackets adjustably engaged therewith to receive shade roller brackets of different lengths and which is provided with holder supporting brackets adapted to be swung into and out of operative positions.

With these and other objects in view, the invention consists of certain novel features of construction, and the combination and arrangement of parts as will be more fully described and claimed.

In the accompanying drawings: Figure 1 is a front view of a portion of a window frame illustrating the application of my improved shade roller and curtain pole support; Fig. 2 is a top plan view of the parts shown in Fig. 1; Fig. 3 is an end view thereof; Fig. 4 is a view similar to Fig. 1 illustrating the application of the support to a double window frame. Fig. 5 is a top plan view of the parts shown in Fig. 4; Fig. 6 is a cross sectional view taken on the line 6-6 of Fig. 1; Fig. 7 is a detail perspective view of one of the frame engaging members of the support; Fig. 8 is a horizontal sectional view of one end of the same; Fig. 9 is a detail perspective view of one of the shade roller brackets of the support;

Fig. 10 is a similar view of the connecting plate for the inner frame engaging members of the support when applied to a double window frame.

My improved shade roller and curtain pole support comprises a pair of frame engaging members each of which consists of a flat bar 1 having thereon near its outer end an inwardly extending tapered or V-shaped frame engaging lug 2, the inner end of which is bent inwardly at right angles to form a combined barb 3 which is adapted to be forced into the outer edge of the window frame at the point where the support is to be arranged. The frame engaging lugs and barbs 3 of the bars 1 are preferably cut and bent from the metal forming the bars 1 as is clearly shown in Figs. 7 and 8 of the drawings. The outer end or extremity of each bar 1 beyond the lug and barb 3 is bent to form an eye or socket 4 the purpose of which will be hereinafter described. The bars 1 may be of any suitable length and have formed therein near their inner ends 75 series of apertures 5. In arranging the bars 1 they are engaged with the outer sides of the window frame at the desired location with the lugs 2 projecting inwardly and engaged with the outer edges of the window frame. When in this position the barbs 3 are forced or driven into the edges of the frame and thus firmly support the frame engaging members or bars 1. The members or bars 1 are held in the position described, 80 by a coiled spring 6 having on its ends hooks 7 which are adapted to be engaged with one of the holes 5 in the ends of the bars 1. When thus engaged with the bars the pressure of the spring is exerted to draw 85 the bars inwardly and to thus hold the barbed lugs 2 thereof in operative engagement with the edges of the window frame.

Slidably engaged with the outer portion of the bars or frame engaging members 1 are shade roller supporting brackets 8 each of which comprises a flat plate corresponding in width to the width of the bars 1 and having their outer ends bent outwardly at right angles to form roller supporting lugs 100 9. In the ends of the lugs of both of the brackets 8 are formed rectangular slots 10

to receive the pintles of the shade roller. By providing both lugs with a rectangular slot the brackets may be reversed or applied to either side of the window frame, 5 thus making it impossible to improperly put up the device. On the opposite edges of the inner ends of the bracket plates 8 are formed flanges which are bent at right angles to the plates and then inwardly to form guides 12 10 which are engaged with the bars 1 of the attaching members, and thus slidably support the brackets 8 on said bars. The bracket plates 8 are preferably formed of spring metal and the outer portions thereof 15 beyond the guides 12 are slightly bowed or bent inwardly from the guides whereby the outer ends of the plates 8 will have a yielding frictional engagement with the outer sides of the bars 1 and by means of this 20 frictional engagement will hold the brackets in their adjusted positions on the bars or frame engaging members, thus permitting the brackets to be arranged for engaging and supporting shade rollers of different 25 lengths.

In connection with the shade roller supports I also preferably provide curtain pole supporting brackets each of which is preferably in the form of a rod 13 having its 30 inner end bent at right angles to form a pintle 14 and its opposite end bent to form a loop 15 which provides a seat for a curtain pole. The pintles 14 on the inner ends 35 of the pole supporting brackets are adapted to be engaged with the sockets 4 in the ends of the bar or frame engaging members as clearly shown in Figs. 2 and 3 of the drawings. When thus arranged the brackets are 40 adapted to be swung outwardly at right angles to the frame engaging members to form supports for the pole and to be swung inwardly above and against the frame engaging members when in an inoperative position as clearly shown in dotted lines in 45 Fig. 1 of the drawings. When the pole supporting brackets are thus swung inwardly, they will be hidden behind the shade roller and will be in an out of the way position when the support is to be employed 50 simply for holding a shade roller.

In Figs. 4 and 5 of the drawings is shown the manner in which my improved supports are applied to a double window frame in which there are no side edges to receive the 55 attaching lugs and barbs of the inner supporting members or bars 1. When the supports are employed in this connection I provide a coupling plate 16 having in its ends apertures 17 and midway between its ends 60 a screw hole 18 adapted to receive a screw whereby the plate is secured to the top cross piece of the window frame midway between the sides thereof. When thus arranged the

barbs 3 on the lugs 2 of the inner members of the supports are engaged with the apertures 17 in the opposite ends of the plate instead of with the edges of the window frame and are thereby secured in position to support two shades and curtains for the double window as will be readily understood. 70

From the foregoing description taken in connection with the accompanying drawings the construction and operation of the invention will be readily understood without requiring a more extended explanation. 75

Various changes in the form, proportion, and the minor details of construction may be resorted to without departing from the principle or sacrificing any of the advantages of the invention as claimed. 80

Having thus described my invention, what I claim is:

1. In a combined shade roller and curtain pole support, a pair of frame engaging members comprising bars having in their inner ends series of apertures and having their outer ends bent inwardly to form sockets, tongues struck out of said bars, with their free ends pointed to form frame engaging barbs, a spring having its ends engaged with the apertures in the inner ends of said frame engaging members whereby the latter are held in yielding engagement with the window frame, shade roller supporting brackets having a sliding frictional engagement with the bars of said frame engaging members and curtain pole supporting brackets pivotally engaged with the sockets on the ends of said frame engaging members. 100

2. In a combined shade roller and curtain pole support, a pair of frame engaging members comprising bars, means on the outer ends thereof to engage the outer edges of a window frame, a spring to yieldingly connect the inner ends of said frame engaging members whereby the latter may be engaged with window frames of different widths, reversible shade brackets comprising plates having on their outer ends right angular lugs provided with rectangular apertures to receive the pintles of the shade roller, flanges formed on the opposite edges of the inner ends of said plates and bent to form guides to receive the frame engaging members, said plates having their outer ends bent inwardly beyond from said guides to form a frictional engagement with the frame engaging members. 110

3. In a combined shade roller and curtain pole support a pair of frame engaging members comprising bars, lugs formed on the outer ends of said bars, barbs formed on said lugs, a spring to yieldingly connect the inner ends of said bars, shade roller brackets slidably engaged with said bars 120

and a coupling plate adapted to be secured to a double window frame and having in its ends apertures to receive the barbed lugs on the ends of the frame engaging members 5 when the supports are applied to a double window.

In testimony whereof I have hereunto set

my hand in presence of two subscribing witnesses.

GILBERT E. ALPHIN.
